UNITED STATES PATENT OFFICE.

MAX SCHALSCHA, OF SUMMIT, NEW JERSEY.

LUBRICATING DEVICE FOR STEAM-HAMMERS.

1,037,332.

Specification of Letters Patent.

Patented Sept. 3, 1912.

Application filed November 18, 1911. Serial No. 661,083.

To all whom it may concern:

Be it known that I, MAX SCHALSCHA, a citizen of the United States, residing at Summit, in the county of Union and State 5 of New Jersey, have invented a certain new and useful Improvement in Lubricating Devices for Steam-Hammers, of which the following is a specification.

The invention relates to means for supplying oil to the steam entering the valve-chamber of a steam hammer. Oil cups located in the steam supply pipe near the valve inlet channel are usually employed but are objectionable for the reason that 15 they deliver the lubricant to the steam at a distance from such channel and for the more important reason that the oil cup projects considerably beyond the face of the hammer and is very liable to damage or 20 breakage by impact against adjacent objects when the hammer is lifted, lowered and swung as required in the extremely rough usage to which the hammer is subjected in practice.

25 The object of my invention is to provide a strong casting firmly attached to the face of the hammer and capable of withstanding the shocks and blows to which it is exposed, serving to receive the steam supply pipe 30 and protect the latter and its valve, and containing a chamber arranged to deliver lubricant to the steam immediately before its entrance to the valve chamber, thus avoiding the above objections.

35 The invention consists in certain novel features of construction and arrangement by which the above objects are attained to be hereinafter described and pointed out in the claims.

40 The accompanying drawings form a part of this specification and show the invention as it has been carried out in practice.

Figure 1 is a face view or front elevation of a pile hammer equipped with the 45 improved oiler. Fig. 2 is a corresponding side view. The succeeding figures are on a larger scale. Fig. 3 is a face view of the lubricating device alone. Fig. 4 is a corresponding top view. Fig. 5 is a vertical section taken on the line 5—5 in Fig. 3. Fig. 6 is a vertical longitudinal section taken on the broken line 6—6 in Fig. 5. Fig. 7 is a corresponding horizontal section on the line 50 7—7 in Fig. 3, showing a portion of the hammer body.

Similar letters of reference indicate the same parts in all the figures.

A is the body of the hammer having a suspending loop A¹ by which it is suspended and placed in position, and a cylinder and 60 ram, not shown, which with other portions of the mechanism may be understood to be of any ordinary or approved type. On the face of the hammer is a raised portion or boss of large area on which is mounted a 65 flanged casting B connected to the steam inlet channel a, and a flanged collar C serving as an exhaust connection leading from an exhaust channel not shown, to the exhaust pipe C¹.

70 The casting B comprises a plate extended as a flange B¹, carrying a cored casing or boss B², in the lower portion of which is a passage b leading from the downwardly presented inlet opening b¹ to the channel a. 75 In the upper portion of the casing, above the passage b, is a chamber b² having an orifice b³ at the top, closed by a screw-plug D. A small hole or passage b⁴ affords communication from the interior of the chamber 80 to the steam passage b at a point near the junction of the latter with the channel a. The casting is strongly bolted to the body 85 of the hammer with the passage b presented to the channel a as shown in Fig. 7. Pieces 85 of felt E or the like are introduced into the chamber b² through the opening b³ to fill the chamber partially and the latter is then supplied with oil and the screw-plug D replaced. The volume of steam rushing 90 through the passage b at each reciprocation of the ram draws a small quantity of oil through the oil passage b⁴ which is carried along by the steam and serves to lubricate 95 the valve and other portions of the mechanism. The oil passage b⁴ is produced by inserting a small drill through the opening b³ and inclining it to the angle permitted by such opening, thus producing an orifice of small diameter having an angular inclination 100 in the direction of the steam current flowing through the passage b so that the current tends by suction to draw the oil from the chamber b². The felt E or other absorbent filling serves to restrain the flow 105 of lubricant and permits a small quantity only to escape at each impulse or rush of the steam current.

110 The casting B is strong and securely fastened to the hammer body and is therefore well

adapted to withstand rough usage; and by locating the steam inlet opening b^1 in the lower portion thereof with the opening directed downwardly, it permits the steam connection to be made close to and parallel with the face of the hammer, and as a consequence of such location and position also serves as a protection for the steam pipe and its controlling valve.

10 Although in this description steam is set forth as the motive force for the operation of the hammer, it will be understood that the invention will serve with compressed air or other medium which may be employed; and although the invention is shown as applied to a pile hammer it will serve successfully with other mechanism of like character to which it may be adapted.

I claim:

20 1. In a steam hammer of the character set forth, a casting comprising in a single integral element an oil reservoir, a steam passage, an inclined passage from the bottom of said reservoir to the steam passage, and 25 a lateral extension of said steam passage for communication with the steam inlet channel of the body of a hammer to which said casting is attached.

2. In a steam hammer of the character set forth, a casting comprising in a single integral element an oil reservoir, a steam passage, an inclined passage at its bottom af-

fording communication between said oil reservoir and the steam passage, and a lateral extension of the said steam passage for communication with the steam inlet channel of the body of a hammer, said reservoir having a filling opening permitting the insertion of means for forming said inclined passage.

3. In a steam hammer of the character set forth, a body portion having a steam channel therein, a casting secured to said body on the face thereof and having a steam passage in its lower portion leading to said channel from an inlet on the under face of said casting, and an oil chamber in the upper portion of said casting, and an oil passage leading from said chamber to said steam passage and communicating with the latter at a point intermediate its ends at an 40 inclination in the direction of the current of steam flowing through said steam passage whereby the volume of steam passing through said steam passage serves by suction to withdraw the oil from the oil chamber 45 through said inclined oil passage.

In testimony that I claim the invention above set forth I affix my signature, in presence of two witnesses.

MAX SCHALSCHA.
